UNITED STATES PATENT OFFICE.

RALPH R. JANES, OF NEW YORK, N. Y., ASSIGNOR TO STANDARD KNITTING MILLS COMPANY, A CORPORATION OF NEW YORK.

KNITTED GARMENT.

1,168,641.

Specification of Letters Patent. Patented Jan. 18, 1916.

Application filed November 8, 1913. Serial No. 799,861.

To all whom it may concern:

Be it known that I, RALPH R. JANES, a citizen of the United States, residing in the borough of Brooklyn, in the city and State 5 of New York, have invented certain new and useful Improvements in Knitted Garments, of which the following is a full, clear, and complete description.

My invention relates to knitted garments 10 and particularly to undershirts and garments of like nature, and has for its object the production of new and improved garments of this kind which, while being pleasing in appearance and comfortable in use, 15 yet may be easily and quickly made and at less cost than has heretofore been possible.

In the drawing accompanying and forming 20 a part of this specification I have illustrated a garment embodying my invention and the manner in which the same is made.

In this drawing Figure 1 shows an elongated knitted tube and the manner in which the same is cut or severed in the middle to form the body portions of two garments. 25 Fig. 2 shows the finished garment, which in this case is an undershirt.

In practising my invention I first provide longitudinally ribbed tubular members such as shown in Fig. 1 suitable in length 30 to form the body portions of two garments. I then sever this double length tube in the middle on a line 2, so laid out that there will result two tubular body portions 1, each having four pointed or inverted V-shaped 35 extensions 3 in the form of isosceles triangles, all equal in size and equally spaced around the edge of the tubular body portion. These extensions preferably have straight edges and these are finished by sewing 40 strips of braid or lace, 4, thereon, which strips extend from each of the front extensions to the corresponding extensions in the rear so as to form shoulder pieces or straps 5, as shown in Fig. 2. By these 45 simple operations a complete garment, please-

ing in appearance and comfortable in use, is produced with a minimum amount of labor.

It will further be seen from the foregoing description that by practising my invention all of the fabric is used and this results in 50 further cheapening the cost of the garments without impairing in any way their quality. In the finished garment the V-shaped extensions are so located as to cover the breast completely and give the lower neck and no 55 sleeve cut so much desired in summer underwear. As the edges on which the strips 4 are sewed are all straight the sewing can be rapidly effected. Furthermore, by cutting the material as above described the 60 shoulder straps are brought into their proper places, so as to be comfortable to the wearer and so that they will not have a tendency to slip from the shoulder, as is frequently the case with garments now on 65 the market.

While I have only described the preferred form of my improved garment and one way of practising my improved method, I am aware that modifications may be made by 70 those skilled in the art without departing from the scope of my claim.

What I claim is:

In a garment of the character described, a body portion consisting of a longitudinally 75 ribbed knitted tube of uniform width throughout, and provided at the upper end, at both front and back, with two integral extensions in the form of isosceles triangles, the bases of which are equal to one-half the 80 width of the tube, and all of the sides of which make substantially equal angles with the ribbing of the material, the upper apex of each front extension being connected to the upper apex of the corresponding back 85 extension, for the purpose described.

RALPH R. JANES.
